UNITED STATES PATENT OFFICE.

ALVAN FOOTE FOSS, OF MONTREAL, QUEBEC, CANADA.

BOTTLE-CLOSURE.

1,229,436.

Specification of Letters Patent. Patented June 12, 1917.

Application filed June 23, 1916. Serial No. 105,369.

To all whom it may concern:

Be it known that I, ALVAN FOOTE Foss, a subject of the King of Great Britain, and resident of 126 Durocher street, in the city of Montreal, Province of Quebec, Dominion of Canada, have invented new and useful Improvements in Bottle-Closures, of which the following is the specification.

The invention relates to improvements in 10 bottle closures as described in the present specification and illustrated in the accompanying drawings that form part of the same.

The invention consists essentially of the 15 novel formation of disk closure whereby a lug is formed on one side and so arranged as to bend easily on being inserted in the bottle and be packed at the corners.

The objects of the invention are to devise 20 a means of facilitating the removal of card disks, particularly from milk bottles, without spilling any part of the contents, to do this and not leave any aperture through which the milk will leak or dust enter and generally to provide a cheap and serviceable 25 closure for milk and other bottles.

In the drawing, Figure 1 is a plan view of a disk closure showing this invention.

Fig. 2 is an enlarged fragmentary view 30 showing the particular formation of the lug.

Fig. 3 is a perspective view of a bottle neck showing the card closure in place.

Fig. 4 is a fragmentary view showing the 35 positions of the lug and adjacent corners of the disk in relation to the bottle neck.

Like numerals of reference indicate corresponding parts in each figure.

Referring to the drawings, the disk 1 of 40 card board or other suitable material is cut out with the lug 2 projecting from the edge thereof, said lug extending from said disk in the fillets 3 and through these fillets the slits 4 are made, said slits terminating at 45 points on the edge of the line of continuation of the circle through said lug.

It will be thus seen that the lug 2 will be more easily turned upwardly on being inserted in the neck of the bottle and that the fillets 3 cut away by the slits 4, being very small pointed ends of card board, will crush 50 inwardly and provide a natural packing for the side of the hinge, where the lug turns upwardly.

All such lugs in milk bottles hitherto have left an aperture on being inserted in 55 the bottle, but this is easy to bend and has the corners formed by the bend filled with the crushed card, which becomes more satisfactory the longer the milk is in the bottle, as the soaking of the card material 60 swells it, especially at the edge wherefrom the fillets are cut away.

In the use of the invention the closure is inserted in the customary manner and the lug turns upwardly or is previously turned 65 and the fillets as explained crush to the neck wall beside the lug. To remove the closure the lug is grasped and the disk pulled out.

What I claim is:—

1. In a bottle closure, a disk having a lug 70 projecting from the edge thereof and said lug having cuts extending inwardly from the side edges of the lug and terminating at the continuation line of the edge through the lug.

2. In a bottle cap, a piece of cardboard having a lug projecting therefrom and fillets formed in the corners produced by the intersection of the sides of the lug and the outer edge of the cap, said fillets being separated from the lug by oblique cuts which terminate at the continuation line of the 80 edge of the cap through the lug.

Signed at the city of Montreal, in Canada this 12th day of May 1916.

ALVAN FOOTE FOSS.
